UNITED STATES PATENT OFFICE

153,338

DESIGN FOR A TIRE BEAD BREAKER

Harold W. Darr, Minneapolis, Minn., assignor to
Thomas O. Nelson, Fergus Falls, Minn.

Application June 9, 1947, Serial No. 139,550

Term of patent 14 years

(Cl. D54—13)

To all whom it may concern:

Be it known that I, Harold W. Darr, a citizen of the United States, residing at Minneapolis, in the county of Hennepin and State of Minnesota, have invented a new, original, and ornamental Design for a Tire Bead Breaker, of which the following is a specification, reference being had to the accompanying drawing, forming part thereof.

Referring to the drawing:

Fig. 1 is a plan view of a tire bead breaker, showing my new design;

Fig. 2 is a front elevation thereof; and

Fig. 3 is a side elevation thereof.

I claim:

The ornamental design for a tire bead breaker, as shown.

HAROLD W. DARR.
